UNITED STATES PATENT OFFICE.

WALTER HONORATO BARKER, OF HARROW, ENGLAND.

CHILD'S FOLDING CARRIAGE.

No. 812,323.

Specification of Letters Patent.

Patented Feb. 13, 1906.

Application filed August 14, 1905. Serial No. 274,173.

To all whom it may concern:

Be it known that I, WALTER HONORATO BARKER, a subject of the King of Great Britain, residing at 22 Butler road, Harrow, Middlesex, England, have invented new and useful Improvements in Folding Carriages for Children, of which the following is a specification.

This invention relates to improvements in folding carriages for children, the object of the invention being to provide a carriage of this description which can be folded up, so as to occupy a minimum of space.

According to the invention I construct the improved carriage of a pair of rectangular frames, hinged together in the usual manner. At each angle at the lower end of each of the frames I pivot a bracket, the said brackets being adapted to carry short axles, upon which the traveling wheels are rotatably mounted. With the arrangement the wheels can be turned with the brackets, so that they occupy a position at right angles to the frames—that is to say, the working position or when the carriage is to be folded a position in a plane parallel with that of the frames. Means such as spring pawls or pins are provided for locking the brackets in the two positions.

In a suitable arrangement for carrying out the invention the hinged frames are held in the extended position by links or a hinged stay, locked by suitable means, such as a catch. A back-frame and handle-bar are hinged to the top of one of the rectangular frames and are held in place by arms which extend to the upper end of the other rectangular frame. The seat is advantageously formed of a strip of fabric, leather, or other suitable material, which is attached to the upper end of one of the hinged frames and extends up the back-frame, to the upper end of which it is attached, the arrangement being such that the fabric or the like is always held taut.

Assuming that the carriage is extended for use and that it is desired to collapse the same, the link-catch is disengaged and the back turned forward and downward, this movement folding the hinged frames, upon which the back and arms ultimately lie and are held in position by a suitable catch. The wheels are then released and turned under the folded frames, in which position they are locked, as above described.

In the accompanying drawings, Figure 1 is

a side view of a folding carriage constructed according to the invention and shown in the extended position. Fig. 2 is a plan view thereof. Fig. 3 is an end view of the carriage. Fig. 4 is a plan view of the carriage in the folded or collapsed position. Fig. 5 is a side view thereof. Figs. 6 and 7 are a side and rear elevation, respectively, of one of the front-axle brackets; and Figs. 8 and 9 are similar views to Figs. 6 and 7, respectively, of one of the rear-axle brackets. Fig. 10 is an enlarged section on the line 10-10, Fig. 3.

a and *b* are the two rectangular frames, which are hinged together at *c*. *d d* are the two front wheels, and *e e* the rear wheels, of the carriage. Each of the front wheels *d* is mounted upon a short axle *f* upon the end of the bracket *g*, pivoted in a bearing-piece *g'*, secured to the lower end of the frame *b*. Each of the rear wheels *e* is similarly mounted upon a short axle *h* upon the end of a bracket *i*, pivoted to a bearing-piece *i'*, secured to the lower end of the rectangular frame *a*, the arrangement being similar to that described with respect to the front wheels *d*. Each of the bearing-pieces *i'* and *g'* is fitted with a spring rod or catch *j*, adapted to lock the brackets *g* and *i* in the extended and collapsed positions, as hereinafter described. These spring-catches engage with the bracket *g* or *i* on either side thereof, so as to prevent its movement until the catch is released.

k k represent links which are hinged together at *k'* and at their other ends to the bottom of the frame *a* and the top of the frame *b*, respectively, so as to form a strengthening-stay when the frames are expanded, the said frames being held in this extended position by means of the catch *l*, which is pivoted near the upper end of the upper link *k* and engages with the transverse bar *m*, rigidly secured to the frame *b*, as clearly shown in Fig. 10.

n is the back-frame, having the handle-bar *n'* and being bolted at its lower end to the top of the rectangular frame *b*, *o* representing the two arms, which are hinged to the lower part of the said back-frame *n* at one end and at the other end to the extremities of extensions *a' a'* at the upper end of the rectangular frame *a*.

p is the seat and back of the carriage, these parts being composed of a strip of fabric, leather, or other suitable material, which is secured at the lower end to the upper end of the rectangular frame *a* and at its upper extremity to a wire frame *p'*. This wire frame

5 *p'*, which is of a U or trough shape, can be secured in guides *q q*, fixed at the rear of the back-frame *n* and so constructed that the said wire frame *p'* can be made to assume two positions, so as to adjust the inclination of the 10 back and seat of the carriage. These two positions are shown in Fig. 1, that in full lines illustrating the position in which the frame *p'* extends forwardly and brings the back *p* forward. In this position the outwardly-turned ends *p*² of the wire frame engage with the ends of the slots *q'*, formed in the guides *q*, and the frame itself bears against the lugs *r* (see Fig. 3) upon the front of the said guides, 15 the slots and lugs serving to hold the frame *p'* firmly in position. The broken lines show the position in which the wire frame *p'* is pushed down in the slots *q'* of the guides *q*, it being held in place by the lugs *r* and the lugs 20 *s*, also provided upon the guides *q* at the rear thereof.

25 *t* is an extension of the seat, the said extension being hinged at *t'* to the front end of the seat proper, *p*, onto which it is folded when not required for use. Fig. 1 shows this extension *t* in both positions.

30 *u* is a footboard which is fitted upon the lugs *u' u*² integral with the front bearing-pieces *g'*, as shown in Figs. 6 and 7. This footboard is provided with a spring-catch *v*, which snaps over the pin *w* upon the handle *n'* when the chair is folded, and so locks it in the folded position.

35 With this construction of carriage it will be clear that when not required for use by releasing the catch *l* the frames *a* and *b* can be folded on the hinge *c*, so that they lie in the same plane, and the back-frame *n* turned down to lie upon these two folded frames. By releasing 40 the spring-catches *j j* the wheels *d d* and *e e* can then be turned so that they lie beneath the folded frames *a* and *b* and are locked in this position by the aforesaid catches. The carriage thus occupies a very 45 small space, as shown in Figs. 4 and 5, and can be conveniently carried. To facilitate its transport by hand, a strap-handle *x* is secured to the frame *b*.

Having now particularly described and ascertained the nature of my said invention 50 and in what manner the same is to be performed, I declare that what I claim is—

1. In a folding carriage, the combination with a pair of hinged frames, of traveling wheels mounted upon short axles attached to 55 brackets hinged to the lower ends of the frames, and means such as a spring-catch for locking the brackets in the extended and folded positions, substantially as hereinbefore described. 60

2. In a folding carriage, the combination of a pair of hinged frames, traveling wheels pivoted thereto in such a manner that they can be folded beneath the same, a back-frame secured to one of the hinged frames, arms 65 connecting the back-frame with the other hinged frame and a flexible seat secured to one of the hinged frames and to the back-frame, substantially as described. 70

3. In a folding chair, the combination of a pair of hinged frames mounted on traveling wheels pivoted with respect thereto, a back-frame rigidly secured to one of the hinged frames, a folding seat, the lower end of which is attached to the other hinged frame and the 75 other end to a wire clip, and of guides upon the back-frame for adjustably securing the wire clip to the back-frame, substantially as hereinbefore described. 80

4. In a folding chair, the combination of a pair of hinged frames mounted on traveling wheels pivoted with respect thereto, a back-frame rigidly secured to one of the hinged frames, a folding seat, the lower end of which is attached to the other hinged frame and the 85 other end to a wire clip, of guides upon the back-frame for adjustably securing the wire clip to the back-frame, a hinged stay connecting the two hinged frames and a catch for locking the hinged frames in the extended 90 position, substantially as described.

WALTER HONORATO BARKER.
